EFISIO CADEDDU, OF VANCOUVER, BRITISH COLUMBIA, CANADA.

STREET SIGNALING DEVICE.

1,372,401.

Specification of Letters Patent.

Patented Mar. 22, 1921.

Application filed September 11, 1920. Serial No. 409,643.

To all whom it may concern:

Be it known that I, EFISIO CADEDDU, a subject of the King of Italy, and a resident of Vancouver, in the Province of British Columbia, Canada, have invented certain new and useful Improvements in Street Signaling Devices, of which the following is a specification.

My invention relates to improvements in signaling devices, with more particular reference to a signal for use in street railway systems for regulating the traffic at street corners and intersections and which is automatically operated by the cars thus doing away with the traffic policeman usually stationed at such points.

I attain this object by the construction illustrated in the accompanying drawings in which—

20 Figure 1 is a perspective view of my device.

Fig. 2 is a top plan view with cover removed.

Fig. 3 is a view of a cylinder.

25 Fig. 4 is a sectional plan view of the assembled cylinders.

Fig. 5 is a view showing the relative positions of the signs.

30 Fig. 6 is a side view showing the depressible rail member.

Fig. 7 is a plan view of the rail bearing plate.

Fig. 8 is a view illustrating the operation of the device.

35 Fig. 9 is a diagrammatic view illustrating the operation of the device.

Similar figures of reference indicate similar parts throughout the several views.

The device consists of a casing 1 having 40 four sides 2, 3, 4 and 5, in which are diametrically opposite openings 6, 7, 8, and 9 respectively. Mounted within the casing and within and concentrically of each other are cylinders 10, 11, 12, and 13, each of which

45 is provided with four openings indicated generally by the numerals 14, 15, 16 and 17, the cylinder openings being twice the width of the casing openings. Half of each of the casing openings is, however, covered with a 50 piece of transparent material, such as mica, as indicated by the numeral 18, thus leaving the other half open and when the parts are in the normal position the uncovered portions of each respective cylinder opening are 55 in line with one another and with the casing openings so that the light from an incan-

descent globe 18^a within the casing shows white through the casing openings. In each cylinder one of the mica portions is colored green while the remaining three portions are 60 colored red. Each cylinder is provided on its upper edge with a lug 19 so that they may be pulled around by suitable wires 20, 21, 22 and 23, respectively attached to the respective lugs and extending through the casing 65 walls 2, 3, 4 and 5, springs 24 being connected to the lugs and the walls as shown for the purpose of returning the cylinders to their normal position after operation as hereinafter described while pivotally mounted 70 spring latches 25 are disposed adjacent each lug to engage behind the same and maintain the cylinder in the position to which it is moved by the pulling of its respective wires, these latches being withdrawn 75 to free the lugs by means of wires 26, 27, 28 and 29 connected to them and extending through the casing walls, as shown in Fig. 4.

In carrying out the working of the invention the assembled device is placed between 80 the car tracks, being suitably supported directly above the street intersecting point so that the openings 6, 7, 8 and 9 are readily observable, as indicated in Figs. 8 and 9, in which two parallel car lines only are shown 85 although the following matter applies with equal force to intersecting car lines. Near the stopping point of the car on line A going in the direction of the arrow is erected on the side walk a column 30 within 90 which is a vertically movable rod 31 the lower end of which is connected to a suitably fulcrumed shaft 32 extending from the rod 31 under the street to engage between the jaws 32^a of a depressible rail member 33 95 one rail being out to admit this member which is placed between the divided ends and extends through a guide slot 34 in a bearing plate 35 fitted under the divided ends. The member 33 projects slightly above the rail 100 so that it will be depressed by the wheel of the car passing over it such depression moving the shaft 32 about its fulcrum point 36 and raising the vertical rod 31, which in turn operates an arm 37 fulcrumed on the 105 upper end of the column and to which the wire 21 is attached, the pulling of which by the arm pulls the cylinder 10 around so that the illuminated green mica portion shows at the casing opening facing the driver of the 110 car on line A while the illuminated red portions show at the three other casing open-

ings. At a point farther ahead on the line A a similar mechanism to that just described is arranged in connection with a second column 38, to the arm 39 of which the latch 5 wire is connected, the operation of the arm pulling the wire to trip the latch and permit the return of the cylinder 10 to its normal position, whereupon the white light shows at all four of the casing openings.

10 The other cylinders are operated in the same manner by means of depressible rail members and the mechanism associated therewith, and the signaling scheme may be briefly described as follows: The device is 15 placed above the street intersecting point and if the streets are car streets it would have four cylinders, and a pair of columns is erected at each corner as described, there being one pair of columns for one cylinder, 20 and the wires of the cylinders are led to the arms of their respective columns. If the intersecting street is not a car street then there would be one pair of columns at the opposite corners and only two cylinders. 25 A car stopping on the near side of a crossing automatically operates its respective cylinder as described so that the green light faces the driver and the red lights face the traffic on the three other streets while at the 30 same time the word "Go" registers above the green light and the words "Stop" above the red lights, these words being printed on the respective cylinders and appearing through suitably disposed slots in them and the casing walls. On starting up and traveling 35 farther along the line the car which first operates the signal depresses the second depressible rail member and trips the latch of the cylinder allowing it to return to normal 40 position when the light will show white on all four sides, thus indicating that all the streets are clear for traffic.

From the foregoing it will be seen that I have devised an automobile signal for regulating street traffic automatically which is 45 simple and efficient in action and comparatively inexpensive to install and maintain.

What I claim as my invention is:—

1. A street car signal comprising a casing adapted to be supported directly above a street intersection provided with rotatable permissive and restrictive signals facing the respective directions of car travel, said signals being normally obscured, and means 50 operated by a car for rotating the said signals into view, the permissive one to face the car operating the signal and the restrictive ones to face other directions of travel.
2. A street car signal comprising a casing adapted to be supported directly above a street intersection, said casing being provided on opposite sides with apertures facing the respective directions of car travel, concentric cylinders mounted within the 55 casing for circumferential movement, there

being one cylinder for each direction of travel, each said cylinder being provided with one permissive signal and three restrictive ones normally obscured, and means operated by a car traveling in one direction 70 for operating the respective cylinder therefor to bring the signals of that cylinder to register with the casing apertures, the permissive one to face the car operating the cylinder.

3. A street car signal comprising a casing adapted to be supported directly above a street intersection, said casing being provided on opposite sides with apertures facing the respective directions of car travel, 80 concentric cylinders mounted within the casing for circumferential movement, there being one cylinder for each direction of travel, each said cylinder being provided with one permissive signal and three restrictive ones normally obscured, means operated by a car traveling in one direction for operating the respective cylinder therefor to bring the signals of that cylinder to register with the casing apertures, the permissive one to face the car operating the cylinder, and means for temporarily locking 85 said cylinder in the signaling position.

4. A street car signal comprising a casing adapted to be supported directly above 95 a street intersection, said casing being provided on opposite sides with apertures facing the respective directions of car travel, concentric cylinders mounted within the casing for circumferential movement under 100 tension, there being one cylinder for each direction of travel, each said cylinder being provided with one permissive signal and three restrictive ones normally obscured, means operated by a car traveling in one 105 direction for operating the respective cylinder therefor to bring the signals of that cylinder to register with the casing apertures, the permissive one to face the car operating the cylinder, means for temporarily locking 110 said cylinder in the signaling position, and means for tripping the locking means to permit return of the cylinder in the signaling position.

5. A street car signal comprising a casing 115 adapted to be supported directly above a street intersection, said casing being provided on opposite sides with apertures facing the respective directions of car travel, concentric cylinders mounted within the 120 casing for circumferential movement under tension, there being one cylinder for each direction of travel, each said cylinder being provided with one permissive signal and three restrictive ones normally obscured, a 125 vertically movable shaft for each car track positioned between the signal and the cars operating the respective cylinders thereof, a depressible member disposed in the path of each car adapted to be depressed by the 130

car passing over it, a connection between each said member and its respective shaft arranged so that depression of the member raises said shaft, a bell crank adjacent the 5 upper end of each shaft and operated thereby, and a flexible connection between the crank and its respective cylinder by the operation of which said cylinder is moved to bring its signals opposite the casing apertures.

6. A street car signal comprising a casing adapted to be supported directly above a street intersection, said casing being provided on opposite sides with apertures facing the respective directions of car travel, concentric cylinders mounted within the casing for circumferential movement under tension, there being one cylinder for each direction of travel, each said cylinder being 10 provided with one permissive signal and three restrictive ones normally obscured, a vertically movable shaft for each car track positioned between the signal and the cars operating the respective cylinders thereof, 15 a depressible member disposed in the path of each car adapted to be depressed by the car passing over it, a connection between each said member and its respective shaft arranged so that depression of the member 20 raises said shaft, a bell crank adjacent the upper end of each shaft and operated thereby, a flexible connection between the crank and its respective cylinder by the operation of which said cylinder is moved to bring its 25 signals opposite the casing apertures, means for temporarily locking said cylinders in the signaling positions, and means similar to the cylinder operating means positioned in advance of them for automatically tripping said locking means.

7. In a street signaling device, normally obscured suitably positioned permissive and restrictive signals, there being a permissive

signal for each direction of car travel and restrictive signals for each other direction, 45 and means operated by the car first reaching a stopping point at an intersection for bringing the permissive signal into view to face the car and the restrictive signals into view to face the other directions of travel. 50

8. A multiple track signaling system comprising signal members corresponding in number to the number of tracks, operating means whereby each signal is operated only by the cars passing over a particular track, 55 each of said signals being provided with individual signal means for each track, and being normally set to indicate a clear passage to all of the tracks but adapted when operated, to set a warning to the cars on all 60 of the tracks with the exception of the track on which the car operating the signal is located.

9. The combination with the preceding claim, of means for automatically resetting 65 the signal members after each operation.

10. A street car signal comprising a rotatable member provided with normally inoperative permissive and restrictive signals and car operated means for rotating said 70 member to cause the permissive signal to face the car operating the member and the other signals to face in the different directions of travel.

11. A multiple track signal comprising 75 signal means arranged to give an individual signal to the cars operating on each track and car controlled means for operating the signal means to display the individual stop or like warning to cars on all of the tracks 80 except the track on which the car operating the signal is located.

Signed at Vancouver, B. C., Canada, this 30th day of August, 1920.

EFISIO CADEDDU.
